Attorney.

UNITED STATES PATENT OFFICE.

JOHN T. OXFORD, OF MORGANTON, NORTH CAROLINA, ASSIGNOR OF ONE-HALF TO
W. T. BERRY, OF MORGANTON, NORTH CAROLINA.

CHECK VALVE.

Application filed February 18, 1928. Serial No. 255,320.

This invention relates to valves, and more particularly check valves.

Check valves, as commonly constructed, are of two general types, namely those employing a swinging gate, and those employing a freely movable ball.

Each of these types has its advantages and disadvantages, and the general object of the present invention is to provide a check valve of a combined type having the advantages of both. In other words, the invention seeks to provide a valve comprising a ball or spherical member which, instead of being free, as usual, is mounted to swing toward and from its seat.

More specific objects of the invention are to so support the swinging ball that it is capable of both rotation on the axis of support and bodily movement along such axis, whereby the ball may readily adjust itself to its seat, and also whereby a constantly changing surface is presented to the seat. Still other objects are to provide improved means for manually adjusting the ball relative to its seat and to so design the valve casing that the ball may be readily inserted and removed therefrom.

In order that the invention may be clearly understood, reference is had to the accompanying drawing forming part of this specification, and in which:

Fig. 1 is a plan view of my improved check valve;

Fig. 2 is a vertical, longitudinal section through the same, substantially on the line 2-2 of Fig. 1;

Fig. 3 is a fragmentary side elevation showing a slightly modified arrangement;

Fig. 4 is a fragmentary detail on an enlarged scale showing the adjusting means; and

Fig. 5 is a vertical sectional view of a slightly modified form of valve.

Referring to the drawings in detail, my improved valve casing preferably consists of a T-shaped hollow casting 1 resembling a standard pipe fitting. This casting comprises the main or body portion 2 and branch portion 3. Viewed another way, the casing comprises a cylindrical member 2 having a lateral opening surrounded by an annular flange 3. The end of this flange or branch and also the ends of the main portion of the

casting are provided with standard pipe threads, as illustrated.

On the inside of the main or body portion of the casting at a point near its junction with the branch, is an annular rib or shoulder 4, and that edge of such rib adjacent the branch opening is machined or beveled as indicated at 5 to form a valve seat. It will be noted that this valve seat is somewhat smaller in diameter than the interior bore of the main portion of the casting so that a tool or reamer may be inserted through the end of the casting for the purpose of machining the valve seat.

Arranged to cooperate with the seat 5 is a valve in the form of a ball or sphere 6. This is supported upon a rod or stem 7 having at one end a head or enlargement 8 on which the ball rests. It will be noted that the opening in the ball through which the rod 7 passes is slightly larger than the rod, so that the ball is free to turn and also free to slide on the rod or stem. In this way the ball can adjust itself to the valve seat and make a tight seal, even though it may not be positioned quite accurately. Furthermore, by virtue of its free rotation on the stem, the ball constantly presents a different surface for engagement with the valve seat.

The upper end of the rod or stem 7 is pivotally attached to an eye 9 having a screw threaded shank 10 which passes through and is threaded in a cap 11 screwed over the end of the branch 3. Cooperating with the edge of this cap is a lock nut 12, and it will be seen that by turning the cap 11 the vertical position of the ball may be adjusted, and that it may be held in adjusted position by screwing the nut 12 up against the cap.

A lock nut 13 is threaded over the other end of the shank 10, as shown, and the extreme end of this shank is provided with a kerf 10^a (see Fig. 4), capable of receiving a screw driver. This constitutes an additional adjusting means for the valve. A washer 14 may be employed underneath the lock nut 13, as shown.

It will be noted that the shank 10 of the eye 9 is set into the cap 11 at a point to one side of the center thereof. This is desirable in order that the point of support of the valve stem may be brought as nearly as possible vertically over the seat 5, so that said

stem assumes an inclined position, as shown in Fig. 2, thus causing the ball 6 to normally rest by gravity against the seat 5, when the valve casing is mounted in a substantially horizontal position, as it is intended to be.

In order to indicate the correct angular position which the cap 11 should occupy, after being adjusted, I preferably place on such cap a mark in the shape of an arrow, as indicated at 15 in Fig. 1, the head of the arrow pointing in the direction in which fluid is discharged from the valve casing, or, in other words, in the direction of flow. In order to drain sediment or foreign matter from the valve casing, I may provide a pet cock, such as shown at 16 in Fig. 2, or instead, an ordinary plug, as indicated at 17 in Fig. 3.

From the foregoing it will be understood that in assembling the parts, the stem 7 is attached to the eye 9, and this set into the cap 11. The ball is then lowered through the interior of the branch 3 into the main passageway, and the cap 11 is turned until the ball is at approximately the proper height, the cap being finally stopped and locked, however, in a position in which the arrow 15 is disposed longitudinally of the valve casing, as shown in Fig. 1. This constitutes the rough adjustment. The final, fine adjustment is accomplished by inserting a screw driver in the kerf 10^a of the threaded shank 10 and, the lock nut 13 being loosened, turning the shank 10 so as to raise or lower the ball exactly to the required extent. The lock nut is then tightened, and the valve is ready for operation.

While I have referred to the valve as a "ball", it will of course be obvious that it need not in all cases, be a complete sphere.

Thus, as shown in Fig. 5, I may employ a block 18 having a curved portion 6' consisting of a segment of a sphere, and adapted to co-operate with the seat 5. This type of construction may be preferable in valves of large size, in order to save weight and material.

What I claim is:

1. A check valve comprising a casing having a seat, a ball valve, and means for suspending said ball so that it may swing freely laterally toward and away from said seat, said means including a rod on which said ball is slidably mounted.

2. A check valve comprising a casing having a seat, a ball valve, and means for suspending said ball so that it may swing freely toward and away from said seat, said means including a rod on which said ball is both slidably and rotatably mounted.

3. A check valve comprising a casing having an opening surrounded by an annular upstanding flange, a cap screwed over the end of said flange, said casing also having a valve seat therein, a ball valve adapted to engage said seat and freely suspended from said cap, whereby the height of said ball relative to said seat may be adjusted by turning said cap, and additional means for adjusting the height of said ball.

4. A check valve comprising a casing having a seat, a valve member having at least a portion of its surface of spherical form, and means for suspending said valve member so that it may swing freely laterally toward and away from said seat, said means including a rod on which said valve member is slidably mounted.

In testimony whereof I affix my signature.

JOHN T. OXFORD.
